UNITED STATES PATENT OFFICE

LEON BENOIT, OF CHICAGO, ILLINOIS

EGG CARTON

Application filed September 14, 1928. Serial No. 305,911.

This invention relates to cartons for eggs and like commodities. It is advantageous in the respects that the carton is reinforced adequately from end to end, it provides a cushion support for the eggs or other contents, and it is ventilated clear through so as to preserve the carton contents in proper condition. The present carton which is characterized by features such as these is, moreover, simple 10 and inexpensive to produce and set up. By way of exemplification of this invention, reference is made to the accompanying drawing wherein—

Figure 1 shows in perspective my carton 15 with the front wall partly broken away to expose more of the interior thereof;

Fig. 2 is a transverse section through the carton taken anywhere intermediately of its ends; and

Fig. 3 is an elevation of a carton having a slightly modified construction.

The present carton is desirably formed of a suitable card board blanked out to the shape required for providing, when bent up 25 into serviceable position, a front wall 4 joined along its lower edge to a bottom 5 which in turn is joined to the lower edge of a rear wall 6 which supports at its upper edge a cover 7 the free edge of which is provided 30 with a depending flap 8. The carton ends comprise in each instance a rectangular inner wall 9 constituting a bent-up extension of the bottom 5, and a pair of tongues 10 which are extended from the front and rear 35 walls to occupy positions along the outer face of the inner wall 9. These tongues, as will be noted from the drawing, present upper edges in mutual alignment with the corresponding edge of the associated wall 9, and 40 although they extend toward each other, they remain separated in the center region of the carton end. Each tongue is in the general form of a truncated right angle triangle with the base vertically disposed along the 45 carton corner, the side which is perpendicular thereto being the top edge of the tongue. The remaining side *a* of the triangle proceeds upwardly and inwardly from the lower end of the base, preferably at an angle of about 45°, and stops short at its juncture

with the line of truncation which is formed by the vertical edge *b*.

Means are provided for securing the tongues so provided to the associated end wall 9, and for this purpose stitching or stapling 55 11 may be resorted to for such interconnection. The end components, when so joined, serve to maintain the carton in a set-up condition ready for use. As it is desirable, however, to collapse the carton for packing, shipping, or storage purposes, I provide in each end wall 9 a bend line *c* coincident with the edge *a* of the tongues which extend from the rear wall 6, and in the front wall 4 I provide two other bend lines *d* each extending 60 from its lower corners thereof at angles of approximately 45°. Bend lines of the kind noted may conveniently be provided by scoring the material of which the carton is made. When so constructed the entire carton may 65 be folded down with the front wall disposed adjacent the bottom, the ends over the front wall, and the cover over the ends.

Within the carton is arranged a filler which, by preference, provides individual 75 cells or pockets for the reception of the eggs or other commodities. A filler which is particularly suited for the purposes of this invention is suggested in Figure 2 wherein I have illustrated a central partition 12 extending longitudinally of the carton to interlock with a series of cross walls 14 with which are interlocked other outer partitions 15 having a swinging mounting by which they may turn from nearly horizontal positions, as 80 shown, to positions which are vertical. When swung to this latter position the filler may be collapsed in its entirety. In each of the cross walls is formed a pair of segmental slots 16 through which are extended body portions 85 17 of the outer partitions, these slotted openings under all conditions, however, being of appreciable area. Cooperating with these openings to promote ventilation through the carton are windows 18 in the end walls 9, 90 these windows being located between the tongues 10, and having desirably a triangular form so as not to be overlapped thereby. The eggs or other contents are receivable 95 in two rows on opposite sides of the central 100

partition 12, where they may rest upon the outer partitions of the carton bottom. I may find it desirable to reinforce the carton in a longitudinal direction and for this purpose utilize, by preference, a plurality of longitudinal corrugations 19 which, as shown, are in two series, one centrally of each row of cells. These corrugations, which are formed in the material of which the carton is composed, may extend for the length thereof, and also vertically of the end walls 9, if desired. Should the carton be equipped with a filler having no bottom support for the eggs, then the latter will be rested directly upon the corrugations which afford thereto a degree of protection somewhat greater than would the flat bottom of the carton.

Referring now to Figure 3, I have illustrated a modification in the carton end wall. 20 In this instance the end wall 20 extends upwardly only as far as the juncture of the edges *a* and *b* so that thereabove and between the two tongues 10 there is an intervening open space constituting a ventilating window. In 25 this construction, as in the other, the tongues are joined to the end wall as by stitching or stapling 11, and in all other respects as well there may be exact similarity.

A carton produced in accordance with my 30 invention is simple, inexpensive, and readily set up for use. It may receive a paraffin treatment by which the material whereof it is made is rendered impervious to moisture and non-absorptive of odors, etc. Manifestly, in various respects it may be changed or altered, and in so far as any such modifications fall within the purview of the appended claims, I would include the same within the scope of this invention.

40 I claim:

1. A carton formed from a cardboard blank bent to provide a front, bottom, back and cover in the order named, the front, back and bottom having integrally formed 45 extensions forming ends for the carton, said bottom and its extensions being provided with transversely spaced groups of longitudinally extending corrugations for reinforcing the carton, the extensions of the front and 50 back being bent at right angles into engagement with the bottom extensions and terminating in spaced relation with their upper edges parallel to the bottom of the box and their lower edges inclined upwardly from 55 the lower corner of the box and defining a bend line, a fastener element securing the extremities of the front and back extensions to the bottom extensions, and a ventilating opening in the end of the box between the 60 front and rear extensions.

2. A carton formed from a cardboard blank and bent to provide a front, bottom, back and cover, the front, back and bottom having extensions forming ends for the car- 65 ton, said bottom and its extensions being pro-

vided with transversely spaced groups of longitudinally extending corrugations for reinforcing the carton.

3. A carton formed from a blank bent to provide a front, bottom, back and cover, 70 the front, bottom and back being provided with extensions which fold inwardly to form an end for the carton, the front and back terminating in spaced relation, and the extensions of the bottom having a portion terminating in spaced relation from the top to provide a ventilating opening above the extensions of the bottom and between the spaced extensions of the front and back.

4. A carton formed from a blank bent 80 to provide a front, bottom, back and cover, the front, bottom and back being provided with extensions which fold inwardly to form an end for the carton, the front and back terminating in spaced relation, the ex- 85 tensions of the bottom having a portion terminating in spaced relation from the top to provide a ventilating opening above the extensions of the bottom and between the spaced extensions of the front and back, the 90 extensions of the front and back having their lower edges inclined to define a bend line for the carton.

In testimony whereof, I have hereunto set my hand this 12 day of September, 1928.

LEON BENOIT.
